UNITED STATES PATENT OFFICE.

FRED HJORTH, OF HARLAN, IOWA.

TIRE-PUMP.

1,392,829.

Specification of Letters Patent.

Patented Oct. 4, 1921.

Application filed July 17, 1920. Serial No. 396,962.

To all whom it may concern:

Be it known that I, FRED HJORTH, a subject of the King of Denmark, and a resident of Harlan, in the county of Shelby and State 5 of Iowa, have invented certain new and useful Improvements in Tire-Pumps, of which the following is a specification.

My invention relates generally to pumps and particularly, although not necessarily, 10 to hand operated tire pumps, a purpose of my invention being the provision of an air pump in which the intake and expulsion of air occurs at each stroke of the piston whereby, the pumping capacity of a pump is 15 doubled as compared to that of the ordinary pump.

I will describe one form of tire pump embodying my invention and will then point out the novel features thereof in claim.

20 In the accompanying drawings:

Figure 1 is a view showing in vertical section and partly in elevation one form of pump embodying my invention.

25 Figs. 2 and 3 are transverse sectional views taken on the line 2—2 and 3—3, respectively.

Referring specifically to the drawings, in which similar reference characters refer to similar parts, H designates generally a head casting, and B a base casting which is connected to the head casting by means of a 30 cylinder designated at C. Working within the cylinder C is a piston designated generally at P which is adapted to be actuated by a piston rod R.

35 As shown in Fig. 1, the head casting H comprises a body portion 15, the under side of which is formed with a collar 16 which is interiorly threaded to threadedly engage the upper end of the cylinder C. The base casting B is likewise provided with a collar 17 which threadedly engages the lower end of the cylinder C. The body portion 15 is formed with an opening arranged axially of the collar 16 and through which extends the 40 piston rod R. The walls of this opening threadedly receive a screw plug 18, such plug being bored to slidably receive the piston R. Within the lower part of the opening of the body portion 15 is arranged wick 45 packing for effecting a lubrication of the piston rod R, such packing being retained within the opening by the plug 18.

The head casting H is provided with lateral extensions 19 in which is formed a 50 pocket 20 that is normally closed by a screw

plug 21. The pocket 20 communicates with passages 22 and 23 formed within the extension 19, and at the junction of the pocket and passages, valve seats 22^a and 23^a, respectively, are formed, upon either of which a ball valve 24 is adapted to seat. That portion of the pocket between the seats 22^a and 23^a is rounded, as indicated at 20^a, so as to permit the valve 24 to roll from one seat to the other during the operation of the 60 pump as will be more clearly described hereinafter. Also communicating with the pocket 20 is a discharge duct 25, the outer end of which communicates with a discharge nozzle 26 that is adapted to be connected 70 to the flexible tube (not shown) as will be understood.

The passage 22 effects communication between the cylinder C and the pocket 20, while the passage 23 connects the pocket 20 75 with a pipe E arranged at one side of the cylinder C and connected to the head and base castings H and B by unions 27 and 27^a, respectively. The unions in turn threadedly engage the walls of suitable sockets formed 80 in the castings, their outer end threadedly receiving cups 29 in which suitable packing is arranged.

The base casting B is concaved on its upper side at a point corresponding to the lower end of the cylinder C as indicated at 85 30. Communicating with this concaved portion 30 is a duct 31 which extends through the casting and into communication with the union 27. By this arrangement it will be 90 seen that the lower end of the pipe E is likewise in communication with the lower end of the cylinder C.

As shown in Figs. 1, 2 and 3, the piston P 95 comprises a disk shaped body 32 formed with a diametrically extending duct 32^a which communicates at a point medially of its ends with the interior of a collar 33 formed in the upper side of the body. The piston rod R is of tubular formation as 100 shown in Fig. 1, and its lower end is threadedly fitted within the collar 33 so as to communicate with the duct 32^a. The collar 33 is also interiorly threaded to receive a lock nut 34 which is designed for the purpose of 105 maintaining a leather cup washer 35 upon the body 32. Interposed between the nut 34 and the washer 35 is a metal washer 36. The lower side of the body 32 is formed with a circular projection 32^b which is threaded 110

to receive a nut 34^a. The nut 34^a likewise maintains upon the body a leather cup washer 35^a and a metal washer 36^a.

As previously stated, the piston rod R is 5 of tubular formation, its outer or upper end being provided with openings 37 for connecting the interior of the rod as well as the duct 32^a with the atmosphere. The upper extreme end of the piston rod is provided 10 with a handle 38 which is adapted to be gripped in manually operating the piston, as will be understood.

In operation, let it be assumed that the piston P is at the upper end of the cylinder 15 C with the rod R in corresponding position. During downward movement of the piston, the valve 24 occupies the position shown in Fig. 1 so that the pocket 20 is out of communication with the cylinder C, but is in 20 communication with the pipe E. It will therefore be seen that as the piston descends the air within the cylinder and beneath the piston is expelled from the latter through the passage 31, pipe E, passage 23, pocket 25 20, duct 25 to discharge nozzle 26. During this downward movement of the piston, air is admitted to the cylinder C at a point above the piston P through the openings 37, rod R, and duct 32^a. From the duct 32^a the 30 air passes upwardly within the cylinder and past the cup washer 35, it being understood that because of the flexible material of which the washer is formed, a constriction of the washer is effected to allow the escapement 35 of air between the washer and the wall of the cylinder. It will thus be seen that when the piston P reaches the lower end of the cylinder the latter is almost completely filled with air, and as this air is not under pressure, the 40 valve 24 will remain upon the seat 22^a. The valve is further maintained in this position by the pressure of the air passing through the pocket 20 and outwardly through the nozzle 26.

45 When the piston P moves upwardly from the bottom end of the cylinder, that body of air above the piston is ejected from the cylinder through the passage 22, the air acting to lift the valve 24 from the seat 22^a and 50 depositing the same on the seat 23^a so as to close the passage 23 and to thus disconnect such passage from the pocket 20. The movement of the valve 24 from the seat 22^a to the seat 23^a is facilitated by virtue of the 55 rounded portion 20^a of the pocket. This efflux of air from the cylinder continues

until the piston reaches the upper end of this stroke, and during such movement air is admitted to the cylinder at a point below the piston P through the piston rod R and the 60 duct 32^a passing beneath the piston and downwardly around the periphery of the washer 35^a.

From the foregoing operation, it will be clear that during the movement of the piston in either direction an expulsion of air 65 from the nozzle 26 is effected and that an influx of air into the cylinder first at one side of the piston and then the other, is also effected. Thus it will be manifest that each 70 stroke of the piston is a working stroke whereby the capacity of the pump is doubled as compared to pumps heretofore proposed.

Although I have herein shown and described only one form of pump embodying 75 my invention, it is to be understood that various changes and modifications may be made herein without departing from the spirit of the invention and the spirit and scope of the appended claim. 80

What I claim is:

A pump comprising, a cylinder, a head casting detachably associated with the upper end of the cylinder, a pocket formed in the head casting, a discharge nozzle supported 85 by the head casting and in communication with said pocket, a screw plug closing said pocket, a passage formed in the head casting and effecting communication between said pocket and the upper end of said cylinder, 90 a second passage formed in the head casting and communicating with said pocket, a base casting detachably associated with the lower end of said cylinder, a passage formed in the base casting, a pipe arranged at one side of the cylinder, said pipe being detachably associated with the base and head castings and in communication with the passage of the base casting and the second passage of the head casting, valve seats formed in the pas- 100 sages of the head casting, a rounded portion arranged between said seats, a ball valve movable in said pocket and adapted to engage either of said seats, a piston movable within said cylinder, and a piston rod connected to said piston and extending exteriorly of said cylinder, said piston and rod being formed to admit air to said cylinder at a point above the piston as the latter is descending and at a point below the piston 110 as the same is ascending.

FRED HJORTH.
